UNITED STATES PATENT OFFICE.

ANNA S. GAW, OF CHICAGO, ILLINOIS.

SLIDING-SOLE.

966,821.

Specification of Letters Patent. Patented Aug. 9, 1910.

Application filed January 15, 1910. Serial No. 538,243.

To all whom it may concern:

Be it known that I, ANNA S. GAW, a citizen of the United States, residing at Chicago, county of Cook, and State of Illinois, have invented a certain new and Improved Sliding-Sole, of which the following is a specification.

My invention relates to a sliding sole and has for its object the production of a device 10 of this character adapted for arrangement upon an ordinary shoe to facilitate ready sliding upon an iced surface, and at the same time to serve as a protection against wear of the shoe-sole during such sliding.

15 A further object is the production of a sliding sole as stated which will be strong and durable and simple of construction, hence of low cost to manufacture.

Other objects will appear hereinafter.

20 With these objects in view my invention consists in a sliding sole characterized as above mentioned and in certain details of construction and arrangement of parts all as will be hereinafter fully described and particularly pointed out in the appended claim.

25 My invention will be more readily understood by reference to the accompanying drawing forming a part of this specification, 30 and in which is illustrated in perspective the preferred form of my device.

Referring now to the drawing 1 indicates the body of my device which is flat and of a peripheral shape substantially the same as 35 that of the shoe-sole upon which it is destined for use. Hence, in view of this qualification, it is understood that no limitation is made to the precise contour and dimensions of the body of the device since the 40 same may vary in these particulars in order to accommodate the specific form and dimensions of the shoe-sole upon which each is designed to be applied. Said body is formed preferably, although not necessarily, 45 of sheet metal from which it may evidently be readily punched. Provided at the front and rear ends of said body at opposite sides thereof are ears 2 and 3 respectively preferably formed integrally with 50 therewith. Said ears extend upwardly from

said body and serve as a means of connection for the extremities of toe and heel straps 4 and 5 respectively which are secured thereto preferably by rivets 6. Said straps, as seen, are of the ordinary buckling type and are adapted to securely bind the device to the foot by passing over the toe and instep thereof in the usual well-known manner. The front end 7 of the body 1 is, as observed, bent upwardly and rearwardly 55 in a gradually rounding manner, such provision being made in order to protect the toe portion of the shoe and also to avert accidents which might occur, when sliding, were it not so rounded; it being clear that 60 with this construction the sole will be adapted to glide over juts or projections upon the surface passed over, which otherwise would cause the tripping of the performer.

Owing to the fact that plate 1 is continuously flat and covers both the sole and heel, the front edge of the heel is prevented from catching on obstructions. By arranging the front strap 4 to overlap the upwardly and rearwardly turned end 7, the leather is secured 75 held in place.

Having described my invention what I claim as new and desire to secure by Letters Patent is:

A sliding sole consisting of a continuous 80 flat metallic plate adapted to cover both the sole and heel of a boot or shoe, the front end of said plate being bent upwardly and rearwardly to pass over the toe of said boot or shoe; securing lugs at each side of the 85 front and back of said plate, the front lugs being positioned to align with the end of the front end of said plate; a securing strap attached to said front lugs and adapted to overlap said upwardly and rearwardly bent 90 end; and a back strap attached to said rear lugs and adapted to embrace the heel and ankle, substantially as described.

In testimony whereof I have signed my name to this specification in the presence of 95 two subscribing witnesses.

ANNA S. GAW.
